CLAIM

The ornamental design for a high pressure seal body, substantially as shown and described.

DESCRIPTION

FIG. 1 is a front perspective view of a high pressure seal body showing our new design.

FIG. 2 is a rear perspective view of the high pressure seal body illustrated in FIG. 1.

FIG. 3 is a front elevational view of the high pressure seal body illustrated in FIG. 1.

FIG. 4 is a top plan view of the high pressure seal body illustrated in FIG. 1.

FIG. 5 is a first side elevational view of the high pressure seal body illustrated in FIG. 1.

FIG. 6 is a second side elevational view of the high pressure seal body illustrated in FIG. 1.

FIG. 7 is a rear elevational view of the high pressure seal body illustrated in FIG. 1.

FIG. 8 is a bottom plan view of the high pressure seal body illustrated in FIG. 1; and,

FIG. 9 is a cross sectional view of the high pressure seal body illustrated in FIG. 1 taken along line 9-9 in FIG. 3.
